UNITED STATES PATENT OFFICE.

ALLIE S. FREED, OF NEW YORK, N. Y.

DESIGN FOR A LAMP.

Application filed January 14, 1924. Serial No. 8,309. Term of patent 7 years.

To all whom it may concern:

Be it known that I, ALLIE S. FREED, a citizen of the United States, residing at New York city, county of New York, and State of New York, have invented a new, original, and ornamental Design for a Lamp, of which the following description, in connection with the accompanying drawing, is a specification.

Fig. 1 is a front view, Fig. 2 is a side view, and Fig. 3 is a top, or plan, view, of a lamp embodying the design.

I claim:—

The ornamental design for a lamp as shown.

ALLIE S. FREED.
